UNITED STATES PATENT OFFICE

JACOB A. SMITH, OF CHICAGO, ILLINOIS, ASSIGNOR TO MAYER MANUFACTURING CORPORATION, OF CHICAGO, ILLINOIS, A CORPORATION OF ILLINOIS

PAPER SHEET HOLDER

Application filed March 30, 1931. Serial No. 526,220.

My invention relates to means for securing paper sheets to a backing member usually in the form of a metal plate and has for its principal purpose the provision of a novel securing means which enables me to so secure the sheets as to give a neat finished appearance thereto without any showing of the openings provided in the sheets for the securing member.

10 More particularly it is a purpose of my invention to provide a novel means whereby the securing strip used to secure the paper sheets to the backing may be made to completely cover the aperture in the paper and 15 the backing so that from the paper side no aperture is visible.

I will describe the preferred form of my invention by reference to the accompanying drawing wherein—

20 Fig. 1 is a plan view of the paper pad such as is used for calendars embodying my invention;

Fig. 2 is a section on the line 2—2 of Fig. 1; Fig. 3 is a similar section showing the completed article;

25 Fig. 4 is a fragmentary detail enlarged to show the appearance of the pad when secured in accordance with my invention; and

Fig. 5 is a perspective view of one end of 30 the securing strap.

Referring now in detail to the drawing, the numeral 6 refers to the backing member which may be of any suitable sheet material such for instance as sheet metal, and to this backing member the sheets 7 are secured by means of the securing strap 8. In general, the manner of securing is as follows: The backing member and the sheets are all punched with spaced apertures and the strap 8 is provided 35 with a downturned tip portion which goes through the apertures provided and is clinched over on the back as indicated at 10 in Fig. 3.

40 The holes punched, however, are round, and heretofore it has been difficult to obscure these round holes by means of the strap to present a suitable appearance. In order to accomplish the covering of the holes, I preferably make the strap slightly long with respect to 45 the distance from outside to outside of the

holes and in addition thereto I make it slightly wider than the diameter of the holes rounding the ends as shown at 11 in Figs. 4 and 5. Then the downturned tip portion 9 extends from the extreme end of the rounded portion 55 11 and is curved upon an arc of a circle so as to just fit against the wall of the round hole provided in the sheets and backing.

It is believed to be obvious, therefore, that if in assembling the device the tip 9 is forced 60 firmly up against the outer wall of the opening as indicated at 12 in Fig. 3, the strap will substantially obscure the opening in the paper and give the appearance desired. In order to be sure that the strap does force its 65 tip outwardly so as to close the opening, the strap in assembling is made at least as long as the distance from the remote edges of the two holes in the paper and backing and preferably just slightly greater than this distance.

Then in assembling, the strap is bowed up as indicated in Fig. 2 to permit ready insertion of its tips 9 into the openings and afterward the strap is caused to crowd against the 75 outside edges of the holes by running the assembly through flattening rolls to level the strap down tightly against the pad.

From the above description, it is believed that the structure and advantages of this device will be clear to those skilled in the art.

Having thus described my invention, what I claim as new and desire to secure by Letters Patent is:

1. A device of the character described 85 comprising a backing member, a bundle of sheets, said sheets and member having aligning spaced apertures of rounded form, and securing means comprising an elongated metal strip of width at least slightly greater 90 than the width of the apertures, said strip having down-turned tip portions curved transversely to fit against the outer walls of said apertures and forced against said walls by said strip.

2. A device of the character described comprising a backing member, a multiple-leaved pad, said pad and member having aligning spaced apertures of rounded form, and securing means comprising an elongated 100

metal strip of width at least slightly greater than the width of the apertures, said strip having down-turned tip portions curved transversely to fit against the outer walls of said apertures and forced against said walls by said strip, said strip having rounded end portions.

3. A device of the character described comprising a backing member, a multiple-leaved pad, said pad and member having aligning spaced apertures of rounded form, and securing means comprising an elongated metal strip of width at least slightly greater than the width of the apertures, said strip having down-turned tip portions, and said strip being at least as long as the outside to outside distance between said apertures whereby to force the tips against the outer wall of the apertures.

4. A device of the character described comprising a backing member, a multiple-leaved pad, said pad and member having aligning spaced apertures of rounded form, and securing means comprising an elongated metal strip of width at least slightly greater than the width of the apertures, said strip having down-turned tip portions, and said strip being at least as long as the outside to outside distance between said apertures whereby to force the tips against the outer wall of the apertures, said tips being curved transversely to fit the outer walls of said apertures.

5. A device of the character described comprising a backing member, a multiple-leaved pad, said pad and member having aligning spaced apertures of rounded form, and securing means comprising an elongated metal strip of width at least slightly greater than the width of the apertures, said strip having down-turned tip portions, and said strip being at least as long as the outside to outside distance between said apertures whereby to force the tips against the outer wall of the apertures, said tips being curved transversely to fit the outer walls of said apertures, and said strip having rounded ends for covering said apertures.

In witness whereof, I hereunto subscribe my name this 19th day of March, A. D. 1931.

JACOB A. SMITH.
